CLAIM

The ornamental design for a food container cover, as shown and described.

DESCRIPTION

FIG. 1 is a top isometric view of a food container cover showing our new design.

FIG. 2 is a bottom isometric view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof.

FIG. 8 is a right side elevational view thereof.

FIG. 9 is a cross sectional view taken from FIG. 3, in the direction of line 3-3;

FIG. 10 is a cross sectional view taken from FIG. 3, in the direction of line 10-10;

FIG. 11 is a cross sectional view taken from FIG. 3, in the direction of line 11-11; and,

FIG. 12 is a cross sectional view taken from FIG. 3, in the direction of line 12-12.

The stippling shown in the Figures represents surface shading and not surface ornamentation. The evenly broken lines represent parts of the article that form no part of the claim. The dot-dot-dash lines represent the designation of partial cross sectional views and form no part of the claimed design.
